CLAIM

The ornamental design for a compression tool, as shown and described.

DESCRIPTION

FIG. 1 is a left side/front/top perspective view of a compression tool of my new design;

FIG. 2 is a right side elevational view thereof;

FIG. 3 is a left side elevational view thereof, with the compression tool in closed, compressing position;

FIG. 4 is a left side elevational view thereof, with the compression tool in open non-compressing, position;

FIG. 5 is a bottom plan view thereof;

FIG. 6 is a top plan view thereof;

FIG. 7 is a front elevational view thereof.

FIG. 8 is a rear elevational view thereof.

FIG. 9 is a fragmentary left side elevational view thereof, with the compression tool in open, non-compressing position; and,

FIG. 10 is a fragmentary left side elevational view thereof, with the compression tool in closed, compressing, position. It will be understood that the materials shown in broken lines on FIGS. 9 and 10 are for illustrative purposes only and form no part of the claimed design.
